(57) **CLAIM**

The ornamental design for an angled eating utensil set, as shown and described.

DESCRIPTION

FIG. 1 is an upper front isometric view of a first embodiment of my new design for an angled eating utensil set;

FIG. 2 is a top view of FIG. 1;
FIG. 3 is a bottom view of FIG. 1;
FIG. 4 is a front view of FIG. 1;
FIG. 5 is a rear view of FIG. 1;
FIG. 6 is a left side view of FIG. 1;
FIG. 7 is a right side view of FIG. 1;
FIG. 8 is an upper front isometric view of a second embodiment of my new design for an angled eating utensil set;
FIG. 9 is a top view of FIG. 8;
FIG. 10 is a bottom view of FIG. 8;
FIG. 11 is a front view of FIG. 8;
FIG. 12 is a rear view of FIG. 8;
FIG. 13 is a left side view of FIG. 8;
FIG. 14 is a right side view of FIG. 8;
FIG. 15 is an upper front isometric view of a third embodiment of my new design for an angled eating utensil set;
FIG. 16 is a top view of FIG. 15;
FIG. 17 is a bottom view of FIG. 15;
FIG. 18 is a front view of FIG. 15;
FIG. 19 is a rear view of FIG. 15;
FIG. 20 is a left side view of FIG. 15;
FIG. 21 is a right side view of FIG. 15;
FIG. 22 is an upper front isometric view of a fourth embodiment of my new design for an angled eating utensil set;
FIG. 23 is a top view of FIG. 22;
FIG. 24 is a bottom view of FIG. 22;
FIG. 25 is a front view of FIG. 22;
FIG. 26 is a rear view of FIG. 22;
FIG. 27 is a left side view of FIG. 22;
FIG. 28 is a right side view of FIG. 22;
FIG. 29 is an upper front isometric view of a fifth embodiment of my new design for an angled eating utensil set;
FIG. 30 is a top view of FIG. 29;
FIG. 31 is a bottom view of FIG. 29;
FIG. 32 is a front view of FIG. 29;
FIG. 33 is a rear view of FIG. 29;
FIG. 34 is a left side view of FIG. 29;
FIG. 35 is a right side view of FIG. 29;
FIG. 36 is an upper front isometric view of a sixth embodiment of my new design for an angled eating utensil set;
FIG. 37 is a top view of FIG. 36;
FIG. 38 is a bottom view of FIG. 36;
FIG. 39 is a front view of FIG. 36;
FIG. 40 is a rear view of FIG. 36;
FIG. 41 is a left side view of FIG. 36; and,
FIG. 42 is a right side view of FIG. 36.
